Boone C. Coker

UNITED STATES PATENT OFFICE.

EGBERT SHEPPERD, OF SAN FRANCISCO, CALIFORNIA.

DESIGN FOR PHOTOGRAPHIC CARD-BOARD.

SPECIFICATION forming part of Design No. 20,350, dated November 25, 1890.

Application filed October 1, 1890. Serial No. 366,787. Term of patent 3½ years.

To all whom it may concern:

Be it known that I, EGBERT SHEPPERD, a citizen of the United States, residing at the city and county of San Francisco, State of California, have invented and produced a new and original Design for Photographic Card-Boards or Backings, of which the following is a full specification, reference being had to the accompanying drawings, forming a part thereof.

Referring to the drawings, Figure 1 is a view in perspective, and Fig. 2 an end view.

The letter A represents the entire card-board, the outer edges of which are beveled, as shown at a. The beveled face of the card-board is colored in alternating sections—that is, section b is of a red, section b' in gold, while section c may be either red or other suitable color harmonizing and pleasing to the eye. If so desired, however, the several colored sections may be so arranged as to

blend one with the other, thereby producing a perfectly-variegated border. By thus forming the mounting-card the general appearance of the photograph is greatly enhanced, 25 and a border is produced which will be more pleasing to the eye.

Having thus described my invention, what I claim as new, and desire to secure protection in by Letters Patent of the United States, is— 30

The design for the photographic card-board A, which consists of alternating contrasting sections on the beveled edges thereof, substantially as set forth.

In testimony whereof I have hereunto affixed my signature in the presence of witnesses.

EGBERT SHEPPERD.

In presence of—

N. A. ACKER,

CHARLES J. ARMBRUSTER.
